UNITED STATES PATENT OFFICE.

NORMAN H. SAUNDERS, OF HOMEWOOD, ILLINOIS, ASSIGNOR TO RESERVE HOLDING COMPANY, OF KANSAS CITY, MISSOURI, A CORPORATION OF DELAWARE.

AUTOMATIC TELEPHONE SYSTEM.

Application filed March 30, 1927. Serial No. 179,443.

The present invention relates to automatic telephone systems, being concerned more particularly with automatic telephone systems of the class in which some of the subscribers' lines are arranged for loop dialing, while others are arranged for so-called simplex dialing.

The broad general object of the invention is the production of suitable arrangements in an exchange of the foregoing character for use when the simplex dialing lines are relatively few in number whereby the switches operate for the most part over loop circuits, suitable arrangements being provided for repeating the simplex dialing impulses into the loop operating circuits.

In keeping with the foregoing, one object of the invention is the production of a new and improved selector repeater arranged to respond to impulses delivered to it over a simplex circuit (a circuit including both sides of the calling line in parallel and a ground return) into a loop circuit for the purpose of operating any connector (or other switch, if any) seized by the selector when the same is operated.

A further object of the invention is the production of a new and improved connector arranged to respond to loop impulses delivered to it and to complete a connection to subscribers' lines in which impulsing and supervision are carried on over a simplex circuit.

Inasmuch as the particular simplex dialing lines under consideration at the present time are party lines of the type in which the different stations are signalled by means of different codes, it is an object of the invention to equip the loop-to-simplex connectors with code selectors so that a called party-line substation may be signalled by means of the correct code.

A further object of the invention is the production of a new and improved relay arrangement for generating the necessary codes for use in signalling the party line substations.

One feature of the new relay arrangement is that, in a progressive counting relay arrangement two impulse circuits are provided, one for operating the relays, and the other for subsequently restoring the relays one at a time.

Another feature of the arrangement is concerned with the provision of contacts

controlled by the counting relays for holding various code circuits closed over a relatively long interval of time in connection with an impulse circuit for grounding the code wires at intervals to produce the necessary combinations of rings.

There are other objects and features more or less incidental to the foregoing. Such objects and features may be understood best after the specification has been considered in connection with the accompanying drawings forming a part thereof.

Referring now to the drawings comprising Figs. 1-6, they show by means of the usual circuit diagrams a sufficient amount of apparatus in a telephone system embodying the features of the invention to enable the invention to be understood.

Fig. 1 is a trunking layout of an automatic exchange of a 1000-line capacity. In such an exchange connectors and one order of selectors are used. It is assumed that there are several hundred loop lines terminating in the exchange, but only 100, or less, simplex lines entering the exchange. A group of selectors, of which the selector repeater SR is one, is provided for handling the calls incoming to the exchange from simplex lines such as the lines of substations A¹ and A². These selector repeaters operate responsive to impulses delivered over simplex circuits and they repeat loop impulses to any of the connectors in the exchange.

A group of connectors, of which the connector C¹ is one, is provided for completing calls to the simplex lines such as the lines of substations A¹ and A². These connectors respond to loop impulses received either from selector repeaters (such as the selector repeater SR) or from the loop dialing lines such as the line of substation A³ after such lines have been extended thereto through the medium of selectors, such as the selector S.

From the foregoing, it will be evident that the selector S, together with the other selectors used for handling calls from the loop lines, and the connector, together with the other connectors arranged to complete calls to the loop lines, are operated over loop circuits including both sides of the calling line in series.

The simplex dialing lines are of the local battery type, while the loop dialing lines are of the common battery type in accordance with standard practice.

Referring now to Figs. 2 and 3, it will be noted that these drawings show in detail the circuits of the substation A¹, the lineswitch LS¹, the selector repeater SR, the connector C¹, and the substation A². Inasmuch as the circuits of the loop dialing lines and switches are old and have been well known for many years, it is thought unnecessary to show such circuits.

Fig. 4 shows the relays of the relay-type code generator, these relays operate to supply grounded impulses to the ten code conductors connected to the bank of the code selector CS, Fig. 3, (individual to the connector C¹) and to the banks of the code selectors individual to the other connectors having access to the party lines. It will be noted that certain contacts of the relays B and E-M of Fig. 4 are not connected together. These contacts connect together and to the code conductor terminals 1-10 in the manner indicated in Fig. 5, the contacts in Fig. 5 have been given the same reference characters as in Fig. 4 and are placed so that the conductors joining them do not cross over one another. This arrangement has been adopted in order to enable the connections to be easily seen, as they are somewhat complicated when the contacts are placed in their natural relay order.

The invention having been described generally, a detailed description of the operation of the apparatus shown will now be given. For this purpose it will be assumed that the subscriber at the simplex substation A¹, Fig. 2, desires to converse with the subscriber at the simplex substation A², Fig. 3. Upon referring to Fig. 1, it will be noted that the number of the line extending to substation A² is 320 and that the complete number is 320-5. The digit 5 is the digit used to operate the code selector such as the code selector CS, Fig. 3, in order to place the proper ringing code on the called line. The dash (-) is used to separate the digit 5 from the remaining part of the number so as to make the number easier to remember.

When the receiver is removed at substation A¹, the usual receiver and transmitter circuits are closed at the upper switch-hook contacts, and, at the lower switch-hook contacts, ground is placed on the center terminal of the ringer through the impulse springs of the calling device, thereby closing a circuit over the upper talking conductor for line relay 202 of the lineswitch LS¹ by way of the upper coil of the ringer. Line relay 202 operates and causes the stepping magnet 200 to advance the wipers 203-205 into engagement with an idle trunk line in the usual manner, at which point the combined cut-off and switching relay 201 operates, extending the conductors of the calling line through the wipers 203 and 205 to the selector repeater SR by

way of its incoming talking conductors 206 and 208. Line relay 222 now operates over both conductors of the calling line and both the left-hand repeating coil windings in parallel. Upon operating, line relay 222 closes a circuit from battery by way of vertical magnet 227 to ground by way of release relay 223. Release relay 223 operates, but vertical magnet 227 does not operate this time owing to the relatively high resistance of relay 223. Relay 223, upon operating, closes a locking circuit for itself and prepares an operating circuit for the vertical magnet at its inner armature, at the same time opening a point in the circuit of release magnet 228. At its upper armature, relay 223 places ground on the release trunk conductor 207 so as to maintain the lineswitch LS¹ operated after the line relay 202 has fallen back due to the operation of relay 201.

When release-trunk conductor 207 is grounded, dial-tone current commences to flow to ground from the dial tone conductor through the right-hand repeating-coil windings. This flow induces a current flow in the calling line to inform the subscriber that he may now dial the number.

When the calling subscriber dials the first digit 3 in the desired number, three interruptions are produced in the line circuit at the impulse springs of the calling device. While the calling device is off-normal, the ringer coils are short circuited by the contacts of the calling device so as to eliminate the ringer impedance during impulsing. Each time the line circuit is interrupted, line relay 222 falls back and opens the initial circuit of release relay 223, at the same time connecting the low round series relay 224 in multiple with release relay 223. The resistance relations between the windings of relays 223 and 224 is such that relay 223 will fall back eventually if shunted continuously by relay 224. Also, the vertical magnet 227 operates through the inner upper contacts of switching relay 226 and the inner armature of relay 223 each time series relay 224 is connected up by relay 222. The vertical magnet receives three impulses and raises the wipers opposite the third level of bank contacts. Due to the speed at which the interruptions are produced, relay 223 remains operated. Due to the copper sleeve on its iron core, relay 224, after having operated in response to the first impulse delivered to the vertical magnet through its winding, remains operated until after the last impulse has terminated.

As a result of the operation of relay 224, a circuit for relay 245 is prepared and is closed immediately upon the off-normal movement of the switch, and a point in the circuit of the rotary magnet 230 is opened, so as to prevent a premature rotary opera-

tion. When its circuit is closed, relay 225 operates and locks itself to the grounded release trunk conductor at its inner armature, at the same time preparing the rotary magnet circuit at its outer armature.

When relay 224 falls back at the end of the vertical movement, it completes the rotary magnet circuit, at the same time opening the initial circuit of the now-locked stepping relay 225. Rotary magnet 230 energizes when its circuit is closed and it advances the wipers 233-235 into engagement with the first set of bank contacts in the third level. Near the end of its stroke, the rotary magnet opens a point in the circuit of relay 225, whereupon relay 225 falls back and opens the rotary magnet circuit. At this point the rotary magnet falls back and closes a point in the stepping relay circuit. If the trunk line terminating in the first bank contact sets is idle, no further rotation takes place and the switching relay 226 operates, seizing the trunk line.

Assuming the trunk line to be busy, relay 225 is operated again through test wiper 224, again closing the rotary magnet circuit. The rotary magnet operates again and advances the wipers another step. This alternate operation continues until an idle trunk line is reached, which trunk line, it will be assumed, is the one comprising conductors 236-238 and extending to the connector C¹. Fig. 3. When this idle trunk is reached, switching relay 226 operates in series with stepping relay 225 in a circuit including the grounded release trunk conductor 207, eleventh rotary step contacts 231, interrupter contacts of the rotary magnet, and the associated off-normal contacts. Relay 225 does not operate at this time owing to the relatively high resistance of relay 226. Upon operating, relay 226 opens a point in the test circuit and connects test wiper 234 to the grounded release trunk conductor 207, thereby making the seized trunk busy immediately; it inserts resistance 232 in the vertical magnet so as to prevent further operations of the vertical magnet and of series relay 224 when the remaining digits are dialed; and at its upper and lower armatures it opens the above mentioned dial-tone circuit and extends the talking conductors to the line wipers 233 and 235.

In the connector C¹, line relay 302, which is connected to the inner terminals of the left-hand repeating coil windings through contacts of reversing relay 301, now operates over conductors 236 and 238, through the wipers 233 and 235 of the selector repeater SR, contacts of switching relay 226, right-hand repeating coil windings, upper contacts of line relay 222, and the current limiting resistance 221. Upon operating, line relay 302 closes a circuit for the slow-acting release relay 303. Relay 303 oper-

ates and prepares the switch for operation by preparing a locking circuit for switching relay 309; closing a point in the operating circuit and opening a point in the release magnet circuit; and placing a multiple ground connection on the release-trunk conductor 237.

When the calling subscriber dials the second digit 2, line relay 222 of the selector repeater SR falls back twice momentarily. Each time it falls back, it shunts the release relay 223 with the series relay 224. Relay 224 and vertical magnet 227 do not operate at this time owing to the inclusion of the resistance 232 in the vertical magnet circuit. It may be pointed out that the resistance 222 may be omitted entirely if desired, in which case the vertical magnet operating circuit is completely open after the switching relay 226 operates. In this case the release relay 223 is maintained operated during impulsing entirely by the local circulating current (brought about by its own self induction) through its own winding and that of the low wound series relay 224. The resistance 232 is included, when desired, so as to cause a slight current to flow through the associated circuit to assist the relay 223 in remaining operated. Each time relay 222 falls back, it opens the D. C. bridge across the talking conductors leading to the connector C¹, with the result that line relay 202 falls back twice momentarily. Each time line relay 302 falls back, it opens the circuit of the slow acting release relay 303 and closes the circuit of the vertical magnet. The vertical magnet circuit, at the time of its first closure, includes the armature of relay 302, normal inner lower armature of relay 303, operated, normally-closed off-normal contacts, and the series relay 304. The vertical magnet receives two impulses. By its operation it raises the wipers 310-312 opposite the second level of bank contacts. Series relay 304 is operated in series with the vertical magnet and opens a point in the circuit of the rotary magnet, at the same time closing a point in the vertical magnet circuit so as to keep such circuit intact after the off normal springs have shifted, as they do upon the first vertical step.

At the end of the vertical movement series relay 304 falls back and transfers the operating conductor from the vertical magnet to the rotary magnet.

When the third digit 0 is dialed, line relay 302 of the connector C¹ is caused to fall back ten times momentarily by the ten momentary interruptions produced by the line relay 222 of the selector SR. Each time it falls back, line relay 302 closes a circuit through the inner lower armature, operated, of relay 303, normally-open off-normal contacts, armature of relay 304, normal, contacts of relay 305, series relay 306, and the

middle lower armature, normal, of relay 309. In response to the ten momentary closures of its circuit, the rotary magnet rotates the wipers 310-312 into engagement 5 with the tenth set of bank contacts in the second level. Relay 306 is operated in series with the rotary magnet, and, being slow acting, it remains operated throughout the digit. Upon operating, relay 306, at its upper armature, disconnects test wiper 311 from the test winding of relay 309 and connects it instead to busy relay 305, at the same time opening a point in the locking circuit of the busy relay. At its lower armature, relay 306 closes a shunt around the associated contacts of relay 305 so as to maintain the rotary magnet circuit intact in case busy relay 305 operates during the rotary movement due to test wiper 311 passing over 20 grounded test contacts.

At the end of the rotary movement, busy relay 305 is energized through test wiper 311 if the called line is busy. In this case, the locking circuit of relay 305 is prepared at 25 the upper armature of relay 305, and a further point is opened in the circuit of the test winding of relay 309. When relay 306 falls back under this condition, it completes the locking circuit of relay 305 to the 30 grounded release trunk conductor 237, with the result that relay 305 remains locked up until the connector is released. No further rotation can take place because the rotary magnet circuit is now open at the inner lower 35 armature of the busy relay. Busy-tone current is placed on the lower talking conductor through the lower armature of the busy relay and the lower armatures of relays 307 and 309. The flow of the busy-tone current 40 is through the lower-right repeating-coil winding to battery through the answering relay 391. The flow of current in this winding induces a current flow in the left-hand repeating-coil windings which passes back 45 over the talking circuit to the calling substation to inform the calling subscriber that the desired line is busy.

Upon hearing this tone, the calling subscriber is expected to replace his receiver 50 and bring about the release of the connection.

Assuming now that the line is idle when called, relay 305 is not operated when the wipers come to rest on the bank contacts of 55 the called line. When relay 306 falls back under this condition, it completes a connection between the grounded release trunk conductor 237 and test wiper 311 including the upper winding of relay 309. This connection includes the upper armatures of 60 relays 305 and 306 and the inner upper armature of relay 309. When a line is idle, there is a battery potential on the test contact thereof (encountered in this case over 65 private normal conductor 314), such bat-

tery being placed on the private normal conductor of the called line through the combined cut-off and switching relay of the lineswitch, (see the lineswitch LS¹, Fig. 2). Relay 309 and the cut-off relay of the 70 called lineswitch operate in series, and the latter relay clears the called line of its normal connection with the line relay of the lineswitch.

In the connector C¹, when relay 309 energizes through its upper winding, it completes a self-locking circuit at its inner lower armature, transfers the operating conductor from the rotary magnet of the connector to the operating magnet of the code selector CS at its middle lower armature; opens the test circuit and connects test wiper 311 directly to ground at its inner upper armature; and at its upper and lower armatures connects up the wipers 310 and 312, at 85 the same time opening a point in the above-mentioned busy tone circuit at its lower armature.

When the calling subscriber dials the code digit 5 assigned to substation A², five current impulses are transmitted over the operating conductor and through the middle-lower armature of relay 309 to the operating magnet of the code selector. As a result, 90 series relay 306 is again operated throughout the digit and the wiper of the code selector is advanced five steps.

When the slow acting series relay 306 falls back at the end of the movement of the code selector CS it closes, at the normally closed contacts controlled by its upper armature, a circuit for relay 305 that was prepared by the off-normal contacts of the code selector CS. Relay 305 thereupon operates and 100 opens the operating conductor at its inner-lower armature, and it prepares the circuit for the release magnet of the code selector CS at its middle-lower armature. At its inner-upper armature, relay 305 connects up 105 the pick-up relay 308 to the pick-up conductor. At this point it will suffice to state that the pick-up conductor is grounded periodically just before the starting of each code period by the code generator shown in Fig. 4, which code generator is started into 110 operation upon the off-normal movement of any connector such as C¹. When the pick-up conductor is again grounded following the operation of relay 307 a circuit is closed 115 for pick-up relay 308. Relay 308 locks itself to ground, at the same time opening its initial circuit. At its lower armature, relay 308 connects the ringing relay 307 to the wiper of the code selector CS. As a result, 120 ringing relay 307 responds to each ground impulse placed on the #5 code conductor by the code generator shown in Fig. 4, the operation of which will be explained subsequently. Each time it operates, relay 307 125 opens the upper and lower talking conductor 130

tors and places ground on the lower line wiper and ringing current from the generator G in the upper line wiper, thereby projecting ringing current out over the called line in accordance with the code assigned to substation A². The small condenser bridged around the upper contacts of relay 307 permits a sufficient amount of ringing current to leak back to battery through the upper right-hand repeating coil winding and relay 301 to cause a mild ringing tone to be sent back to the calling substation.

When the called subscriber responds to the ringing of the bell in accordance with the code assigned to his station, ground is placed on conductors 313 and 315 of the called line at the lower switch-hook contacts through the midpoint of the ringer coils. When this occurs the answering relay 301 operates through the associated repeating-coil windings and over the two conductors of the called line in parallel. At its lower armature it opens a point in the circuit of the connector release magnet and closes a circuit through the middle lower armature of relay 305 for the release magnet of the code selector. The code-selector release-magnet now operates and restores the code selector to normal, whereupon the circuit of relay 305 of the connector is opened at the off-normal contacts of the code selector. Relay 305 falls back and opens the code-selector release-magnet circuit, at the same time opening the circuit of the pick-up relay 308. Pick-up relay 308 falls back and disconnects the ringing relay 307 from the wiper of the code selector.

As a further result of the energization of relay 301, the connection between the left-hand repeating-coil windings and the windings of line relay 302 are reversed, thereby bringing about a reversal of the current flow in the conductors 236 and 238. This reversal is of no particular utility at this time, but may be used, for example, for giving supervision and for similar purposes when the call is coming from an operator's switchboard.

The two subscribers may now converse with each other, the talking circuits being outlined by the heavy lines.

When the conversation is completed, both subscribers replace their receivers. When the receiver is replaced at the called substation, relay 301 falls back and reverses the current supply connections to the incoming conductors back to normal, at the same time preparing a circuit for the release magnet of the connector.

When the receiver is replaced at the calling substation, the line relays of the selector repeater and the connector both fall back, and a moment later the release relay 223 of the selector repeater SR falls back, as well as the release relay 303 of the con-

nector C¹. When both relays have fallen back, the switching relays 201 and 226 of the lineswitch LS¹ and the selector repeater SR fall back. When relay 226 falls back it closes at its inner-upper contacts a circuit for release magnet 228 including the series relay 224. Series relay 224 operates again and reoperates stepping relay 225, which relay extends its operating ground to the release trunk conductor 207, making the selector repeater SR busy during release. When the normal position of the switch is reached due to the operation of the release magnet 229, the off-normal contacts 229 open, whereupon relay 224 falls back, thereby removing ground from release conductor 207 and deenergizing relay 205.

In the connector C¹, the usual release-magnet operation takes place responsive to the deenergization of relay 303, restoring the switch to normal in the usual manner.

Referring now to Figs. 4 and 5, the operation of the code generator will be described. In Fig. 4, the relays A, B and C are the impulsing relays, while the relays D—N are the counting relays. When ground is placed on the start conductor due to a connector, such as the connector C¹, Fig. 3, moving from its normal position and closing its off-normal contacts, relay A operates through the associated resistance and closes a circuit for relay B, at the same time removing the short circuit from around the winding of relay B. Relay B operates and closes a circuit for relay C, at the same time removing the short circuit from around the winding of C. Relay C operates and places a short circuit around the winding of relay A. Relay A falls back when it is short circuited by relay C. Upon falling back relay A replaces the short circuit around the winding of relay B and opens the circuit to B. Similarly relay B replaces the short circuit around the winding of relay C and opens the circuit to relay C. Relay C thereupon falls back and removes the short circuit from around the winding of relay A. As will be apparent, relays A, B and C now reoperate, the reoperation being followed by the falling back of the relays one after the other in the above manner. This operation continues as long as the start conductor remains grounded.

As will be seen from the following part of the description, the entire device passes through a definite cycle of operations, there being fourteen distinct positions in each cycle. The device as a whole is in position 1 with relays A—C operated and it is in position 2 when relays A—C have all fallen back. When the relays have all operated the second time the device is in position 3, and when they have all fallen back the second time the device is said to be in position 4. In all odd numbered positions of the de-

vice, relays A—C are operated, and in all even numbered positions of the device relays A—C are restored. It will be understood of course that there is no clean cut 5 division between the different positions of the device as regards the operation of relays A—C, as they operate and reoperate continuously without hesitation. It will be noted that each relay is provided with a 10 proper collar on its armature end. This is for the purpose of making the relay slightly slow in pulling up so as to render the operation less rapid. It will be noted further that when one of the relays falls back it does so 15 because its winding is short circuited. Therefore the relays fall back rather slowly due to their self induced circulating currents. It has been found that the device works best when the relays A—C are adjusted to go through a complete circle of 20 operations in about one second. Consequently, each relay pulls up and falls back once per second.

The relays D—N operate as follows: 25 Upon the operation of relay C when the device is in position 1, a circuit is closed through contacts of relays F and M for relay D, the circuit being from battery on the contacts of C to ground on the start conductor. Relay D operates and closes a 30 locking circuit for itself in series with relay E, but relay E does not operate immediately due to the fact that it is short circuited as long as C is operated. Relay D also closes 35 a circuit for relays H and I in series, whereupon both of these relays operate. It will be noted that the operating position and the falling-back position of each of the relays D—N is given in parenthesis above each 40 relay so as to enable the operation to be followed more readily.

In position 2, the initial circuit of relay D is opened, whereupon relay E operates in series with relay D, relay D remaining operated. 45 Relay E closes a circuit for relays F and G in series, whereupon relays F and G operate. Relay F disconnects the relay-C impulse conductor from relay D and connects it instead to relay J. The result is 50 that relay J operates when relay C is re-operated in position 3 of the device. Relay J closes a locking circuit for itself in series with relay K, but relay K does not operate until the device passes into position 4 and 55 the initial circuit of relay J is opened. Relay J remains operated in series with relay K, and relay K operates.

Upon operating, relay K closes a circuit for relay N through contacts of relay D. 60 Relay N operates and places ground on the pick-up conductor so as to enable the waiting connectors to start to ring at the beginning of a code cycle. Relay N also closes a circuit for relays L and M in series, where- 65 upon these relays both operate. Relay M

opens the relay C impulse circuit, and prepares an impulse circuit through the upper contacts of relay B. Relay M also closes circuits shown in Fig. 5 so as to start the delivery of the ringing codes. The generation of the codes will be discussed after the description of the operation of the relays has been completed.

When the devices arrive in position 5, a short circuiting impulse is delivered by relay B to the junction of relays D and E. This impulse is a ground impulse from the grounded start conductor and its path includes the upper armatures of relays M and B. When the ground potential is delivered 75 to the junctions of the winding of relays D and E, through an operated armature of relay E, relay D is short circuited and falls back, opening the initial circuit of relays H and I. Relays H and K however remain 80 operated in series with each other owing to the fact that their circuit is closed through contacts of relay H. Relay D also opens the circuit of relay N, whereupon relay N falls back and terminates the pick-up impulse, 85 at the same time opening the initial circuit of the now-locked relays L and M.

With the device in position 6, the impulse delivered through the contacts of B is terminated, whereupon relay E falls back, having been maintained operated after the falling back of relay D solely through the upper contacts of relay B. Upon falling back, relay E transfers the relay B impulse conductor through an operated armature of G to 100 the junction of relays F and G. Relay E also opens the initial circuit of the now-locked relays F and G.

From a consideration of the foregoing description and from an inspection of the 105 drawings it will be apparent that relay G falls back in position 8; that relay H falls back in position 9; that relay I falls back in position 10; that relay J falls back in position 11; that relay K falls back in position 110 12; that relay L falls back in position 13; and that relay M falls back in position 14. It will be apparent also that relay M falls back responsive to the deenergization of relay B, and that relay C is still operated 115 when relay B falls back. That being the case, position 1 of the device follows immediately after position 14, as relay M opens the B-relay impulse circuit and recloses the C-relay impulse circuit. While relay C is 120 falling back, after its circuit is opened and its short circuit is replaced by relay B, relays B, H and I operate again in position 1 of the device, following which the above described operations of the relays take place 125 in the next cycle.

Referring now to Fig. 6 it will be noted that the codes, placed on the ringing code conductors 1—10, consist of various numbers 130 of long and short rings. The long rings are

produced from the steadily grounded conductor 402, Fig. 5, through armature M^2 of relay M, while the short rings are delivered from conductor 401 through armature B^1 of relay B and armature M^1 of relay M. The code conductors will now be considered in order and the way in which the codes are placed on these conductors in accordance with the table shown in Fig. 6 will now be explained.

Considering the code conductor 1, the code placed on this conductor consists of one long impulse. This impulse is started when relay F falls back in position 7, while relay I is still operated. The path of the impulse from the grounded conductor 402 includes armature F^1 , armature I^2 , and armature I^1 . This impulse circuit is opened at armatures I^2 and I^4 when relay I falls back in position 10, and it is not again closed until the position 7 is reached in the next cycle of operations.

Considering now the two short impulses placed on code conductor 2, these impulses are delivered from the impulse conductor 401 under the control of armature B^1 . Conductor 2 is connected to conductor 401 through armature G^3 when armature M^1 is operated in position 4 and it remains so connected until relay G falls back in position 8. The first short impulse is delivered to conductor 2 when relay B operates in position 5, and the second short impulse is delivered when relay B operates in position 7. Relay G falls back and disconnects conductor 2 at the beginning of position 8.

Regarding conductor 3, the three short impulses are delivered to this conductor in a manner similar to that described in connection with conductor 2, the difference being that the connection between conductors 401 and the impulse conductor 3 includes armature 13, which remains operated until the device goes into position 10. As a result, code conductor 3 receives an impulse in position 5, another in position 7, and another in position 9.

Considering now impulse conductor 4, the code placed on this conductor is for short impulses. It will be noted that code conductor 4 is connected to the impulse conductor 401 through contacts L^1 and K^1 until relay K falls back in position 12. Accordingly, code conductor 4 receives an impulse in each of the positions 5, 7, 9 and 11.

Considering code conductor 5, the code placed on this conductor is one long pulse and one short pulse. The long pulse is delivered from conductor 402, starting in position 4 when contacts M^2 is closed, and continuing until position 8 is reached when the pulse circuit is opened at armature G^2 , terminating the long pulse. When relay H falls back in position 9, a connection is closed from the impulse conductor 401 through

armatures K^1 , H^2 , and I^1 for placing the short pulse on code conductor 5. This short pulse is terminated at the end of position 9 upon the falling back of relay B, and the path between conductor 401 and code conductor 5 is opened at armature I^1 when relay I falls back in position 10.

Considering code conductor 6, the code placed on this conductor is one long impulse and two short impulses. The long and short impulse placed on code conductor 5 while the device is passing through positions 4-9 is also placed on conductor 6, as the two conductors are connected together at armature I^1 during such positions. After conductor 5 is disconnected from conductor 6 at armature I^1 at the beginning of position 10, the connection between conductor 6 and conductor 401, including armatures K^1 and H^2 remains until it is broken at armature K^1 when relay K falls back at the beginning of position 12. The second short impulse is placed on conductor 6 when conductor 401 is grounded at armature B^1 in position 11.

Considering now the code placed on code conductor 7, this code is two long pulses, the pulses being placed on the conductor in positions 7-9 and in positions 11-13. The first pulse is placed on code conductor 7 from conductor 402 through armatures F^1 and I^2 when relay F falls back at the beginning of position 7 while relay I is still operated. Relay I falls back at the beginning of position 10 and terminates this impulse. At the beginning of position 11, relay J falls back and starts the second long impulse at armature J^1 . This second impulse is terminated when conductor 402 is ungrounded at the beginning of position 14 by the falling back of relay M.

Considering code conductor 8, the code on this conductor is one short impulse and one long impulse. The short impulse is placed on conductor 8 through armatures E^1 and L^2 while the device is in position 5. The connection between impulse conductor 401 and code conductor 8 is closed at armature L^2 when relay L operates in position 4. When relay E falls back in position 6, code conductor 8 is disconnected from impulse conductor 401 and is connected to code conductor 1, with the result that it receives a long impulse in positions 7-9 at the same time that code conductor 1 is receiving its single long impulse.

Regarding code conductor 9, it will be noted that conductor 9 is connected to conductor 8 through armatures M^3 and J^2 until relay J falls back at the beginning of position 11, at which time the short pulse and long pulse have been placed on conductors 8 and 9. The complete code for conductor 9 is one short pulse and two long pulses. Accordingly, conductor 9 must receive a second long pulse through armatures J^1 and J^2 .

This second long pulse is received in positions 11—13, at which time it will be noted that conductor 9 is receiving its second long pulse at the same time that conductor 7 is receiving its second long pulse, the pulse on both conductors being terminated when conductor 402 is ungrounded at M² at the beginning of position 14.

The code on code conductor 10 is two short pulses and one long pulse. Conductor 10 is connected to impulse conductor 401 through armature G¹ in position 2 of the device, and it remains so connected until the device reaches position 8, receiving a short pulse in position 5 and another in position 7. When relay H falls back at the beginning of position 9, a connection is closed at armature H¹ through armature K² between conductors 10 and 402. This connection remains closed until relay K falls back at the beginning of position 12, causing a long pulse to be placed on conductor 10 in positions 9, 10, and 11.

What I claim is:

1. In an automatic telephone system, a telephone exchange terminating subscribers' lines, a large portion of said lines being arranged for loop operation, while only a small portion of the lines are arranged for simplex operation over the two sides of the line and a ground return, selectors and connectors in said exchange for completing calls initiated on loop lines, said switches being operated according to the loop system of control, and selector repeaters in said exchange for extending to connectors connections originated on the simplex lines, said selector repeaters being arranged to operate over a simplex circuit and to repeat loop impulses to the connectors.

2. In a telephone system, a telephone exchange terminating subscribers' lines arranged for simplex operation, a connector switch having access to such lines, said connector switch being arranged to respond to the loop system of control, a reversing relay in said connector for reversing the current supply connections to its incoming talking conductors, and a circuit for said relay including the two sides of any called simplex line in parallel and a ground return.

3. In a telephone system, a connector switch having access to subscribers' lines, means for operating said connector to extend a connection to a line, a party-selecting device, means effective during the setting up of a connection for operating said device to select the wanted station, means for applying signalling current in accordance with the setting of said device, and means for terminating the application of signalling current upon the response of the subscriber at the called station by releasing said device.

4. In a telephone system, a connector having access to subscribers' lines, means for

operating said connector to extend a connection to a line, a party-selecting device, means for operating said device in accordance with a party digit in the number to select the station on a called line to be signalled, and means for terminating the application of signalling current upon the response of the subscriber at the called station by releasing said party selecting switch, the operating means of said switch being again responsive if the calling subscriber dials another digit after the called subscriber has replaced his receiver to make another station selection and cause a further application of ringing current to be made to the called line.

5. In a telephone system, an automatic telephone exchange comprising selectors operated according to the loop system of control, selectors operated according to the simplex system of control, all of said simplex-operated selectors being adapted to repeat impulses according to the loop system of control, a plurality of connectors operated according to the loop system of control accessible to all of said selectors, lines arranged for loop operation accessible to some of said connectors, and lines arranged for simplex operation accessible to other of said connectors.

6. In a telephone system, a selector operated over a calling subscriber's line on the loop system of control, a selector repeater operated over a calling subscriber's line on the simplex system of control, the talking conductors of said second selector being in non-conductive relationship with the talking conductors of the calling line, a connector accessible to either of said selectors, said connector including means maintained operated over a calling line when the first mentioned selector is used for maintaining the connector in its operated position, and means effective if said selector repeater is used for also maintaining said first named means operated to prevent the release of the connector.

7. In a telephone system, a selector operated over a calling subscriber's line on the loop system of control, a selector repeater operated over a calling subscriber's line on the simplex system of control, the talking conductors of said second selector being in non-conductive relationship with the talking conductors of a calling line, a connector accessible to either of said selectors, said connector including means maintained operated over a calling line when the first mentioned selector is used for maintaining the connector in its operated position, and means effective if the selector repeater is used for also maintaining said first named means operated to prevent the release of the connector, said last named means being in the selector repeater.

8. In a telephone system, a connector operated on the loop system of control and having a relay maintained operated over a loop including a calling subscriber's line for controlling the release of the connector, a selector repeater having incoming and outgoing talking conductors in non-conductive relationship with each other, said selector repeater being directly controlled over calling subscribers' lines and having access to said connector, and means in said selector repeater for controlling said first named relay over a circuit excluding a calling line.
9. In a telephone system, a connector operated on the loop system of control and having a relay maintained operated over a loop including a calling line for controlling the release of the connector, a selector repeater operated from calling subscribers' lines on the simplex system of control, and repeating impulses under the loop system, having access to said connector, and means in said selector repeater for maintaining said relay in the connector operated over a circuit excluding a calling line.
10. A telephone connector switch having incoming talking conductors, a source of potential connected to said conductors, two outgoing talking conductors, each terminating in a wiper, a relay for reversing the potential connected to the incoming talking conductors, said relay being controlled over a circuit including both of said wipers connected in parallel.
11. In a telephone system, a connector switch, a plurality of lines accessible thereto, means for directly operating said connector in accordance with two digits of a telephone number to select a desired line, a party selecting device, means controlled over the connector for operating the device in accordance with a third digit of the desired telephone number to transmit characteristic ringing current to the called line, and means effective responsive to the answering of the call for releasing the device thereby stopping the transmission of the ringing current.
12. In a telephone system, a connector switch, a plurality of lines accessible thereto, means for directly operating said connector in accordance with two digits of a telephone number to select a desired line, a party selecting device, means controlled over the connector for operating the device in accordance with a third digit of the desired telephone number to transmit characteristic ringing current to the called line, means effective responsive to the answering of the call for releasing the device thereby stopping the transmission of the ringing current, and means effective responsive to the termination of the call by the called party for reestablishing an operating circuit for said device under control of the calling party, whereby the calling party may again reoperate the device to recall the called party.
13. In a party line telephone system, means including an automatic connector switch and a party selecting device individual thereto for extending a connection to a desired party line and for signalling the desired party thereon, means for subsequently releasing said connector switch, and means effective before the connector switch is released and after a desired party has been signalled for restoring and reoperating the party selecting device to again signal a desired party on the called line.

In witness whereof, I hereunto subscribe my name this twenty-eighth day of March, 1927.

NORMAN H. SAUNDERS.
